UNITED STATES PATENT OFFICE.

ADALBERT SCHMALZ AND ALBAN SCHMALZ, OF CHICAGO, ILLINOIS.

ANNUNCIATOR.

1,164,224.

Specification of Letters Patent. Patented Dec. 14, 1915.

Application filed April 3, 1914. Serial No. 829,332.

To all whom it may concern:

Be it known that we, ADALBERT SCHMALZ and ALBAN SCHMALZ, citizens of the Republic of Brazil, residing at Chicago, in the county of Cook and State of Illinois, have invented a certain new and useful Improvement in Annunciators, of which the following is a specification.

The essential object of this invention is to provide an annunciator of that type which is adapted to be placed within a street car or similar conveyance and which will indicate the names of streets or stations. The names to be exposed to view are placed *seriatum* upon a fabric web, which can be advanced one step at a time as each successive station is reached and passed, and the operation of the apparatus is controlled by the motorman or a guard, whose post of duty need not be at all near the annunciator.

In the drawings, Figure 1 is a front elevation of the annunciator; Fig. 2 is a side elevation, taken at a right angle to the view of Fig. 1; Fig. 3 is a view similar to Fig. 2, showing some of the parts in different positions from those depicted in Fig. 2; Fig. 4 is a detail of the device for locking the web in place; Fig. 5 is a view looking downwardly from above in Fig. 4; Fig. 6 is a section on the line 6—6, Fig. 3; Fig. 7 is a section on the line 7—7, Fig. 3; Fig. 8 is a section on the line 8—8, Fig. 1; Fig. 9 is a section on the line 9—9, Fig. 10; Fig. 10 is a section on the line 10—10, Fig. 9; Fig. 11 is a section on the line 11—11, Fig. 8; and Fig. 12 is a section on the line 12—12, Fig. 11.

The web 1 of fabric or other flexible material is wound upon spools or reels 2 and 3 (Fig. 8) and bears the names of streets or stations (Fig. 1), which names are successively exposed in the proper order as the feeding mechanism is actuated. Rollers 4 and 5 are provided over which web 1 travels, said rollers being carried upon shafts 6 so mounted that such part or length of the web 1 as is exposed is kept stretched taut. As the car travels in one direction the web 1 is wound upon spool 2, and unwound from spool 3, but when the car travels in the opposite direction, the web is wound upon spool 3. As best shown in Fig. 1, the feeding mechanism is duplicated upon each side of the machine, one set of mechanism being adapted to work in one

direction, and the other set in the opposite direction.

The various movable parts are supported upon a base 10 made of wood or other similar material which can be secured to the wall of the car or conveyance and to this base frame two supporting framewise members 11 are attached, there being one of such members upon each side of the base. The base 10 is secured in such way that the web 1 is presented to the view of the passengers in the car, the passengers being able to see the annunciator as the same appears in Fig. 1 of the drawings. The mechanism for actuating and feeding the web is preferably mounted upon the sides 11, the mechanism at the right of Fig. 1 being faced and geared so as to feed the web from bottom to top, and the mechanism at the left of Fig. 1 being adapted to feed the web from top to bottom. Since the mechanism at the left of Fig. 1 is substantially a duplicate of that at the right, it should be understood that there are two air cylinders 12, two piston rods 13, and so on, although for convenience of description, the singular number rather than the plural is hereinafter employed in describing the web-feeding mechanism.

The cylinder 12 within which the rod 13 reciprocates, is supported upon a bracket 14 secured to the base 10, and upon a bracket 15 secured to the side 11. Compressed air from a suitable source of supply (not shown) is fed to said cylinder through the pipe 16, and when the same enters said pipe 16, flowing toward the top (Figs. 2 and 3) the piston rod 13 is forced toward the top and each upward movement of the piston 13 is converted into a forward-feeding step of the web 1. As previously stated, the web 1 is adapted to be wound upon spool 3 simultaneously as it is unwound from spool 2, and vice versa, and the mechanism which is actuated by the cylinder and piston 12 and 13, is adapted to actuate one of the spools and to advance the web 1 by winding the same upon that particular spool to which the piston is connected.

The spools 2 and 3 are mounted, respectively, upon shafts 17 and 18, and at one end of each of said shafts is a pinion 19 which meshes with and is driven by the gear 20 (Figs. 2 and 3). Shaft 21 upon which the gear 20 is mounted is secured to a side 11 and said shaft bears a relatively large boss 22 around which the sleeve or collar 23 is

adapted to rotate (Figs. 9 and 10). The sleeve 23 is perforated at 24 and the rod 25, bearing the toothed end 26, is pivoted at 27 to the collar 23, the toothed end 26 being adapted to coöperate with the ratchet wheel 28 which is keyed at 29 upon the shaft 21, it being understood that the gear wheel 20 is also keyed or otherwise permanently secured to the shaft 21 so as to rotate in synchronism therewith. When the rod 25 is moved toward the top, Fig. 9, it will act as a pawl and will lock with the ratchet wheel 28, and at each upward movement, Fig. 9, complete reciprocation of the rod 25 will cause a partial revolution of the gear 20. This partial revolution of said gear 20 will be communicated through the pinion 19 and shaft 17 to the spool 2, and it follows that each such partial revolution of the gear 20 will cause the web 1 to be fed forward because of the winding of the web upon the spool which is actuated or driven by the gear 20.

As previously stated, an air-hose or other source of compressed air supply is connected to the nipple 16 and when compressed air is allowed to enter through said nipple, the piston 13 is forced toward the top, Figs. 2 and 3, and this movement of the piston 13 is translated into movement of the rod 25. The rod 25 does not move in a simple straight line, but is adapted to swing upon the pivot 27 as an axis and to move around the shaft 21, first in a clockwise direction and then in a counter-clockwise direction, being adapted to lock with the ratchet 28 during its counter-clockwise movement and thus advance the web 1. Said rod 25 is supported only at the pivoted end, the same being the top end, Figs. 2 and 9, and its other end is loose, being provided with a head 30. Rod 25 also bears a boss 31, and the stirrup 32 is looped over the rod 25 intermediate the head 30 and the boss 31. The stirrup 32 (Figs. 2 and 7) carries an eyelet 33 by which it is connected to one end of the helical spring 34, the other end of said spring being secured to an arm 35 slotted at 36 and retained by means of screws 37 to the side 11, the arm 35 accordingly being mounted so as to permit some regulation of the tension of the helical spring 34. A lever 38 (Figs. 2 and 3) is pivoted at 39, the short shaft 39 being supported between the strap 40 and the bracket 41, said strap 40, in turn, being bolted at 42 to the side 11, the side 11 being preferably beaded at 43 to prevent any lengthwise motion of the straps 40. The left end (Figs. 2 and 3) of the lever 38 is shown in the drawings as being broken away, but it may be provided with a handle or other means whereby the same can be conveniently grasped, and thus permit the lever 38 to be moved from the position of Fig. 2, which is the starting position, to the

position of Fig. 3 by manual operation and thus enable the annunciator to be operated independently of the compressed air. At its upper end (Fig. 7) said lever 38 bears a short shaft 44, around which shaft the boss or sleeve 45 is adapted to rotate. Said sleeve 45 is perforated at 46, and the rod 47 passes through the perforation 46. Said rod bears a nut 48 and the wooden ball 49 upon one side of the rotating sleeve 45, and upon the other side bears the nuts 50 so that members 48 and 49 one on side and 50 on the other serve to secure the link 47 to the boss 45. Link 47 is pivoted at 51 (Figs. 2 and 7) to the top end of the piston rod 13 and, hence, as the piston rod 13 is forced outwardly from the cylinder or toward the top in Figs. 2 and 7, the lever 38 will be caused to rock upon the shaft 39 as an axis, and will move from the position of Fig. 2 toward the position of Fig. 3. The stirrup 32 is pivoted at 52 to the arm or link 53 and this arm or link 53 encircles the shaft 44 preferably intermediate the lever 38 and the boss 45. The upward reciprocation of the piston rod 13 is accordingly communicated by means of link 53 to the stirrup 32, which said stirrup being U-shaped and being looped over the rod 25 (Fig. 7) serves to pull the rod 25 from the position of Fig. 2 to the position of Fig. 3. When the rod is moved from the position of Fig. 2 to the position of Fig. 3, its toothed end 26 will ride over the ratchet 28, but after the parts have moved to the position of Fig. 3, the helical spring 34 will contract and will return all parts normally to starting position depicted in Fig. 2, and as the parts are thus returned because of the contraction of said spring, moving from the position of Fig. 3 to the position of Fig. 2, the rod 25 will lock with the ratchet 28 that is secured upon the shaft 21, and in an obvious manner will translate the counterclockwise movement of the rod 25 and sleeve 23 into a longitudinal advance of the exposed length of the web 1.

The operation of the parts which have just been described in detail is such that normally the tendency would be that each longitudinal reciprocation of the piston rod 13 will rotate the spools 2 or 3 exactly the same number of degrees as any other reciprocation, but means must be provided to prevent that species of uniformity of operation, because to rotate the spool 3 when the web is only partly wound therearound, as in Fig. 8, would not advance the web the same number of inches as would result from the rotation of the spool 2, in said Fig. 8. In other words, to rotate the spool 3, Fig. 8, when a relatively small length of the web is being carried upon that spool might advance the web say six inches, whereas to rotate the spool 2 carrying a relatively large length of the web might advance the web

ten inches. In order to secure the best operating results, however, the web 1 must be advanced the same number of inches at each operation, thus making it necessary so to construct the operating parts that the particular spool which is rotated at any time will rotate through the proper number of degrees will vary from time to time.

In order to secure that necessary result and method of operation the web 1 is provided with eyelets 55 at each edge and these eyelets are separated from each other by uniform distances. The eyelets coöperating with other parts, hereinafter described in detail, predeterminedly stop the advance of the web; and when any eyelet reaches a predetermined point, the forward feeding of the web ceases and the particular sign (such as the word "State" or "Clark" indicated on Fig. 1) opposite to any particular pair of eyelets 55 is held in exposed position. In the view of Figs. 2, 3, and 8, for example, the web is adapted to be wound upon the spool 2, which is rotated in the clockwise direction, causing the web to advance from bottom to top in said figures and is being unwound from the spool 3, which said spool is also adapted to rotate in a clockwise direction as the web is unwound from said spool 3. Said spool 3 carries the ratchet 56 and coöperating with said ratchet 56 is the pawl 57. By means hereinafter described in detail, the successive eyelets 55 cause the actuation of the pawl 57 each time that one of the eyelets reaches or passes a predetermined point, and when the pawl 57 is thus actuated, it locks with the ratchet 56 and by so locking with the ratchet prevents further unwinding of the web from the spool. In other words, the pawl 57 may stop the action of the parts prior to the time that the helical spring 34 has completely contracted and prior to the time that the rod 25 may have moved to its limit in the counterclockwise direction, which limit is reached when the head 30 strikes the stop 58. By predeterminedly tripping the pawl 57 and carrying the same against the teeth of the ratchet 56, therefore, the feeding of the web 1 is stopped whenever the web has advanced a predetermined lineal distance and in this manner the web is, at each operation, fed forward a predetermined lineal distance regardless of the number of degrees of arc through which the spools 2 and 3 may have to rotate in order to feed the web for that distance.

The means for tripping the pawl 57 and causing the same predeterminedly to lock with the ratchet, are best shown in Figs. 4, 5, 8, and 11. Extending from one side of the annunciator to the other is a rod 59, which rod is permitted to have a slight rocking movement, and which rod, near the ends, is flattened out at 60, said flattened portions

being better able to coöperate with the traveling web than rounded portions would be. The pawl 57 is pivoted at 62 to the side 11 and pawl 57 bears a projecting ear or lug 63 to which the helical spring 64 is secured at one end, the opposite end of spring 64 being secured to the end 65 of the trigger 66, said trigger being pivoted at 67 to the side 11. A straddle or bridge 68 is permanently bolted at 69 to each side 11, said straddles 68 being recessed and being connected to a support 71 which extends downwardly from the apex of the member 68 and is secured within the side 11. The flattened ends 60 of the rod 59 are slotted at 72, the post 71 being received within said slots.

As indicated in Fig. 8, the eyelets 55 are thicker than the body of the fabric 1 and when the parts, so far as the eyelets 55 are concerned, are in the position shown in Fig. 8, the flattened end 60 of the rod 59 will be pushed toward the apex of the straddle 68, but when an eyelet 55 passes between the underside of the apex of the straddle 68 and the flattened end 60, said eyelet will engage the flattened end 60 and will trip the rod 59 carrying the same a short distance transversely to the axis of said rod but parallel to the direction in which the web is moving. The trigger 66 bears an arm 75 (Fig. 5) which extends over the edge of side 11, and said arm 75, together with the trigger itself forms an L-shaped member. The arm 75 is recessed at 76, and to the flat part 60 is secured a finger 77 which seats in recess 76. When the eyelet 55 (moving with the arrow Fig. 5) strikes the flat blade 60, the blade 60 is forced toward and into engagement with the arm 75. This causes the trigger 66 to rock upon its pivot, the trigger pulls the pawl 57, and the pawl seats in the ratchet 56, thus locking the spool 2 or 3 against movement, and preventing further feeding of the web 1 even if the spring 34 has not contracted entirely. The post 71 is integral with the beading 78 which is seated in the apex of the straddle 68. Whenever one of the eyelets 55 passes across the bar 59, therefore, said button must pass between the bead 78 and the flat blade 60, thus making sure that each eyelet 55 will trip the trigger 66 and thus lock the web 1 against further travel after each eyelet reaches the bead 78. A shaft 80 extends from one side 11 to the other, bearing a cam 81 at each end, each cam being provided with a toe 82. When that cam 81 shown in Fig. 4 is rotated as designated by the arrow, the toe 82 engages the trigger 66 and locks the same so that the pawl 57 cannot engage the ratchet 56. The cams 81 are so fixed that one trigger 66 is free to move while the other is locked. In Fig. 4, for example, the cam is so turned that the trigger can move, whereas in Fig. 8 the trigger is locked and the pawl 57 re-

tained in place beyond reach of the teeth of the ratchet 56.

The web 1 is fed forward (*i. e.*, toward the top or bottom of Fig. 1 as the case may be) because of the contraction of spring 34, and in order to prevent too rapid movement of the web, which would result in unnecessary shock and jar, brakes are provided for the rollers 4 and 5. These brakes lock the rollers in place, and compel the web 1 to slide thereover, instead of permitting free rotation, and the friction thus caused retards the movement of the web 1. The rollers 4 and 5 are carried upon shafts 6, and at one end of each shaft 6 is a boss or head 83 (Fig. 3) secured by pin 84, and this boss 83 is encircled and engaged by the friction band 85. One end of said band is pivoted at 86 to arm 87 and the other end is connected by pin 88 to link 89. The arm 87 is substantially L-shaped and at 90 is connected to pitman 91. The bracket 92 is secured to the side 11 by screws 93 and carries the stud 94 by which the lever 95 is pivotally mounted. Pitman 91 is slotted at 96 and pin 97 upon the lever 95 fits in slot 96. Lever 95 is itself slotted at 98 and a pin 99 upon sleeve 23 seats in said slot. The parts being as shown in Fig. 2, and the piston rod 13 being forced outwardly from the cylinder 12, the parts move as indicated by the arrows thus releasing the clutch of the band upon the boss 83, the positions then assumed being shown in Fig. 3. When the spring 34 contracts, the parts move in the direction opposite that indicated by the arrow in Fig. 2. (except the pinion 19) thus setting the brake, which is normally kept tight by spring 100.

In the apex of the straddle 68 is the bead 78, and the web 1 must pass between bead 78 and the flattened end 60 of bar 59. When the eyelet 55 passes over bar 59, the bar is depressed, and the lever 95 actuates the parts which insure the return of bar 59 to normal position. An ear 102 (Fig. 11) projects downwardly from flat end 60 and is pivoted to link 103, which, in turn is connected at 104 to a boss 105 secured upon shaft 80. A link 106 is slotted at 107 and 108, and slot 107 (Fig. 3) receives the pin 110 (Fig. 11) which projects outwardly from boss 111 which is keyed to shaft 80. Slot 108 receives the pin 112 fixed to the lever 95, and as the lever 95 is rocked in a clockwise direction (Fig. 3), therefore the link 106 will rock shaft 80 in a counter-clockwise direction, thus moving flat end 60 against or toward the bead 78 and clamping the web 1 in place, the parts being normally retained in that position by the spring 100.

In Fig. 1 it will be seen that there is some space between the two streets or stations named upon the web. This space is intended to be used for advertising matter or the like. An arm 114 is secured to the shaft

80 and to this arm the helical spring 115 is fixed. The spring is retained at 116 in the bracket 117 and normally keeps the shaft 80 in the position shown in Fig. 4 of the drawings, movement of the shaft beyond that point being prevented by the pin 118.

The operation of the machine is as follows: The conduit or pipe which is connected to the nipple 16 is controlled by a valve (not shown) adapted to be operated by the motorman. When the valve is open compressed air enters the cylinder 12, forces the piston 13 outwardly therefrom, rotates the sleeve 23 and the rod 25 in a clockwise direction, carrying the parts from the position shown in Fig. 2 to that shown in Fig. 3. When the parts have moved to the positions of Fig. 3, the compressed air in the cylinder will have exerted its force, whereupon the helical spring 34 will contract and will move the sleeve 23 and connected parts in a counter-clockwise direction, during which movement the sleeve will be locked to the shaft 21 and the rotation of the shaft will cause the gears 19 and 20 to revolve, the rotation of the gears being translated into longitudinal feeding of the web 1. As soon as the spring 34 has begun to contract and the sleeve 23 to rotate in the counter-clockwise direction, the lever 95 and link 91 will also be moved because the pin which is secured upon the sleeve 23 and which is received within the slot at that end of the lever 95 nearest the base 10 will rock said lever upon its axis 94, thus permitting the spring 100 to contract and tighten the friction brake, thus retarding the movement of the web 1 by locking the roller 4 against rotation. When the web is moved so far that one of the eyelets 55 strikes the flat end 60 of the rod 59, said rod will be moved so that the trigger 66 will be rocked upon its pivot, and the pawl 57 will be caused to seat in the ratchet 56, thus stopping further unwinding of the web 1 from the spool 3 and stopping that movement even before the spring 34 may have entirely contracted. At each time that the cylinder 12 is filled with compressed air, therefore, the web 1 will be fed forward for a distance equal to the distance between adjacent buttons 55. The web will feed forward at a fairly rapid rate since the actuating force is on spring 34, but this feeding will be stopped each time that an eyelet 55 strikes the end of the bar 59. The bar which is thus displaced and which is moved toward the base 10 and away from the apex of the straddle 68 is returned to normal position by the members 102 and 103. During the time that the cam 81 on one side of the annunciator locks the triggers 66 upon the same side, the pawl 57 upon that same side will lock with its ratchet 56 and will prevent feeding of the web in one direction. The shaft 80 with its cams 81 are rocked each

time it is desired to release the pawl 57 from the ratchet wheel to allow the web to be fed so as to change the name of the street displayed. This is accomplished by pulling 5 the lever 25 which turns the wheel 23 and through the intermediate connecting mechanism rocks the shaft 80. When the web has been fed through the machine the shaft 80 can be reversed and the side which was free 10 to actuate during the first operations is locked and vice versa. In order to retard still further movement of the device and prevent unnecessary shock and jar, the brake shown in Fig. 12 is provided, the same comprising 15 a head 120 carried upon the spring 121 which is fastened to the side 11, the head 120 being adapted to press against the surface of the member 56. The bar 59 remains in engagement with the eyelet last actuated 20 until said bar is retracted by the toe 82 of the cam 81, which lifts the trigger 66, and moves the pawl from engagement with the ratchet wheel 56, and simultaneously moves the bar 59, to release the eyelet. From this 25 it will be noted that both the web and the ratchet are simultaneously locked at the end of each partial movement of the web and are simultaneously released at the beginning of the next movement.

30 I claim as my invention:

1. An annunciator comprising a pair of spools, a web adapted to be unwound from one of said spools and to be wound upon the other, a shaft for each of said spools, a ratchet in connection with the shaft, means for cooperating with the ratchet thereby to rotate the spool and advance the web, projecting members carried by the web, a pawl adapted to be actuated when one of said 40 members passes a predetermined point, a ratchet carried upon the spool from which the web is being unwound, said pawl being adapted predeterminedly to cooperate with said ratchet and lock the spool which bears 45 said ratchet against rotation.

2. An annunciator comprising a pair of spools, a web adapted to be unwound from one and to be wound upon the other, a shaft for one of said spools, a ratchet upon said 50 shaft, a sleeve encircling the ratchet, a pawl carried by said sleeve and adapted to cooperate with the ratchet, a stirrup looped over said pawl, and means for reciprocating the stirrup thereby to actuate the pawl.

55 3. An annunciator comprising a pair of spools, a web adapted to be unwound from one of said spools and to be wound upon the other, a shaft for each of said spools, means adapted intermittently to rotate one 60 of said shafts and thereby advance the web,

tripping members carried upon the web, a pawl, a ratchet engaged by said pawl and connected with the spool from which the web is being unwound, said pawl being adapted predeterminedly to cooperate with 65 said ratchet, and lock one of the spools against rotation, a bar having flattened ends over which the web passes, said flattened ends being adapted to be engaged by said projections, and means adapted to translate the movement of said bar into movement of said pawl, an L-shaped trigger adapted to be engaged and actuated by said bar, and means connecting said trigger to 70 said pawl.

75 4. An annunciator comprising a pair of spools, a web adapted to be wound upon one and unwound from the other, a shaft for one of each of said spools, a ratchet in connection with said shaft, a sleeve encircling the ratchet, a pawl pivoted to said sleeve and adapted to cooperate with the ratchet, said pawl extending outwardly beyond said sleeve, means controlled by the operator for rotating said sleeve and said 80 pawl in one direction and including a stirrup looped over said pawl, and a spring adapted to move said sleeve and said pawl in a return direction.

85 5. An annunciator comprising a pair of spools, a web adapted to be unwound from one and to be wound upon the other, a shaft for one of said spools, a ratchet upon said shaft, a sleeve encircling the ratchet, a pawl carried by said sleeve and adapted to cooperate with the ratchet, a stirrup looped over said pawl, and compressed air means for reciprocating the stirrup.

95 6. An annunciator comprising a pair of spools, a web adapted to be unwound from one of said spools and to be wound upon the other, a shaft for each of said spools, means adapted to intermittently rotate one of said shafts and thereby advance the web, tripping members, a pawl, a ratchet engaged by 100 said pawl and connected with the spool from which the web is being unwound, said pawl being adapted to lock said last named spools against rotation, a bar over which the web passes, an L-shaped trigger adapted to be 105 engaged and actuated by said bar, and means connecting said trigger to said pawl.

110 In testimony whereof we hereunto affix our signatures in the presence of two witnesses.
